ADJUSTABLE CURTAIN FIXTURE

Mitchell Lipski, Chicago, Ill.

Application April 23, 1941, Serial No. 389,972

5 Claims. (Cl. 156—22)

The present invention relates to new and useful improvements in adjustable curtain and drapery fixtures for windows and has for its primary object to provide, in a manner as hereinafter set forth, a device of this character which is adapted to be expeditiously lowered in a manner to permit the curtains or draperies to be conveniently mounted thereon and adjusted while standing on the floor.

Another very important object of the invention is to provide a fixture of the aforementioned character which may be readily adjusted to meet various conditions.

Still another very important object of the invention is to provide a fixture of the character set forth which may be swung to an out-of-the-way position with the curtains and draperies thereon, and without disturbing said curtains and draperies for permitting access to be had to the window for washing or other purposes.

A still further important object of the invention is to provide a fixture of the character described which necessitates comparatively little damaging of the window frame when the device is mounted thereon.

Other objects of the invention are to provide an adjustable curtain and drapery fixture which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a window, showing a fixture constructed in accordance with the present invention mounted thereon.

Figure 2 is a perspective view, showing the adjustable connection for the horizontally extending curtain rod.

Figure 3 is a cross sectional view, taken substantially on the line 3—3 of Figure 2.

Figure 4 is a perspective view of the lower end portion of the adjustable and rotary post, showing the turning means thereon.

Figure 5 is a view in front elevation of the supporting bracket and the portion of the post which is mounted therein.

Figure 6 is a view in side elevation of the portion of the invention shown in Figure 5.

Figure 7 is a view in horizontal section, taken substantially on the line 7—7 of Figure 6.

Figure 8 is a detail view in vertical section, taken substantially on the line 8—8 of Figure 6.

Figure 9 is a top plan view of a modification.

Figure 10 is a cross sectional view, taken substantially on the line 10—10 of Figure 9.

Figure 11 is a detail view in perspective of the coupling or connection of the modification.

Referring now to the drawings in detail, it will be seen that the reference numeral 1 designates a substantially U-shaped bracket of suitable metal which is rigidly secured through the medium of screws 2 in a vertical position on one side of a window frame 3. The horizontally projecting upper and lower end portions of the substantially U-shaped bracket 1 have formed therein vertically aligned openings, the lower opening being comparatively large.

20 Rotatably and slidably mounted in the aforementioned openings in the horizontal end portions of the bracket 1 is a post or standard 4 of suitable metal. Mounted on the post 4 and rotatable in the lower end portion of the bracket 1 is a sleeve 5. The sleeve 5 is provided, on its upper end, with a flange 6 which rests on the lower end portion of the bracket 1 in a manner to rotatably support said sleeve thereon. A set screw 7 releasably secures the post 4 in adjusted position in the sleeve 5. Angular, inturned retaining fingers 8 are provided on the lower end portion of the bracket 1 and engaged over the flange 6 for rotatably securing the sleeve 5 in position. Pivotedly mounted on the lower end portion of 30 the post 4 is a substantially rectangular handle 9 for turning or rotating said post when desired.

Extending downwardly from the upper end of the post 4 is an integral, inclined arm 10 which terminates in an upwardly curved or substantially hook shaped free end portion 11. Mounted on the end portion 11 of the arm 10 is a metallic tubular coupling 12 which is substantially oval in cross section. The coupling 12 adjustably secures a curtain rod 13 in position on the arm 10 through the medium of a set screw 14 threadedly mounted in said coupling. As shown to advantage in Figure 3 of the drawings, the set screw 14 is engageable beneath the curtain rod 13. In Figure 1 of the drawings, a pair of curtains on the rod 13 are indicated at 15'.

It is thought that the manner of using the device will be readily apparent from a consideration of the foregoing. Briefly, when it is desired to mount the curtains on the rod 13, the set screw 7 is backed off or loosened thereby permitting

ting the post 4, with said rod 13 thereon, to slide downwardly on the bracket 1. Thus, the curtains may now be conveniently mounted on the rod 13 and adjusted while standing on the floor. The edge portion of the curtain which is adjacent the post 4 may be clamped between the upturned end portion 11 of the arm 10 and the rod 13. After the curtains have been adjusted the post 4 is raised to the desired elevation and again secured by tightening the set screw 7. The rod 13 may be conveniently adjusted longitudinally as desired by simply loosening the set screw 14. As the post 4 is rotatable on the bracket 1, the rod 13, with the curtains thereon, may be swung around at any time to an out of the way position without disturbing said curtains when full access to the window is desired, as for cleaning. The construction and arrangement is such that the fixture may be expeditiously installed and said fixture will be inconspicuous when mounted in position on the window frame.

In Figures 9, 10 and 11 of the drawings, a pair of spaced, parallel curtain and drapery rods are indicated at 15. The rods 15 are adjustably secured in position on the free end portion 11 of the arm 10 through the medium of a substantially U-shaped coupling 16 of suitable metal. The end portions of the coupling 16 are provided with three aligned openings 17 for the reception of the rods 15 and the arm 10. Sett screws 18 in the coupling 16 secure the rods 15 in adjusted position in said coupling. The operation of this embodiment of the invention is substantially similar to that of the form shown in Figs. 1 to 8, inclusive, of the drawings.

It is believed that the many advantages of an adjustable fixture constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

1. A curtain fixture comprising a bracket mounted on a window frame, a post mounted for vertical sliding adjustment on said bracket, means for releasably securing said post in adjusted position on the bracket, an arm on the upper end of the post, a curtain rod, and means adjustably connecting said rod to said arm.

2. An adjustable curtain fixture comprising a bracket mounted on a window frame and including a horizontally projecting portion having an opening therein, a sleeve journaled in the opening and including a flange on its upper end resting on the bracket, retaining fingers on the bracket engaged with the flange for rotatably securing the sleeve in position, a post mounted for vertical sliding adjustment in the sleeve, means for releasably securing the post in adjusted position in the sleeve, and a curtain rod mounted on the upper end portion of said post.
3. An adjustable curtain fixture comprising a substantially U-shaped bracket mounted on a window frame and including horizontally projecting end portions having vertically aligned openings therein, a sleeve journaled in the lowermost opening and including a flange resting rotatably on the lower end portion of the bracket, retaining fingers on said lower end portion of the bracket engaged with the flange for rotatably securing the sleeve in position, a post extending slidably and rotatably through the upper end portion of the bracket and the sleeve, means for securing the sleeve to the post for rotation therewith and for securing said post in adjusted position on the bracket, and a curtain rod mounted on the upper end portion of the post.

4. An adjustable curtain fixture comprising a bracket mounted on a window frame, a post mounted on said bracket, a downwardly inclined arm on the upper end of the post terminating in an upwardly curved free end portion, a coupling sleeve mounted on said free end portion of the arm, a horizontally extending curtain rod adjustably engaged in said coupling, and means for releasably securing the rod in adjusted position.

5. An adjustable fixture of the character described comprising a post, means for mounting said post on a window frame, an arm on the upper end of the post, said arm including an upwardly curved free end portion, a substantially U-shaped coupling mounted on the arm and depending therefrom, said coupling having aligned openings in its end portions, certain of said openings for the reception of the arm, a pair of parallel, horizontal rods adjustably engaged in the remaining openings, and means on the coupling for releasably securing the rods in adjusted position on said coupling.

MICHELL LIPSKI.
